DESIGN FOR A COMBINATION OF INK BOTTLE AND CAP

Henry F. Soper, Montclair, N. J., assignor to
L. E. Waterman Company, New York, N. Y., a
corporation of New York

Application March 11, 1933. Serial No. 47,436

Term of patent 14 years

To all whom it may concern:

Be it known that I HENRY F. SOPER, a citizen of the United States, residing at Montclair, in the county of Essex and State of New Jersey, have invented a new, original, and ornamental Design for a Combination of Ink Bottle and Cap, of which the following is a specification, reference being had to the accompanying drawing forming a part thereof.

In the drawing:

Fig. 1 is a perspective view of a bottle and cap constructed according to my novel design.

Fig. 2 is a face view in elevation of the structure shown in Fig. 1.

I claim:

The ornamental design for a combination of ink bottle and cap substantially as shown.

HENRY F. SOPER.
